(57) **CLAIM**

The ornamental design for a tool container, as shown and described.

DESCRIPTION

FIG. 1 is a front perspective view of a tool container shown in the closed position;

FIG. 2 is a rear perspective view;

FIG. 3 is a front view thereof;

FIG. 4 is a left side view thereof;

FIG. 5 is a top view thereof;

FIG. 6 is a rear view thereof;

FIG. 7 is a bottom view thereof;

FIG. 8 is a front perspective view of the base portion of the tool container with the top removed (the broken line showing drill bits is for illustrative purposes only and forms no part of the claim);

FIG. 9 is a rear perspective view of the base portion of the tool container;

FIG. 10 is a front view of the base portion of the tool container;

FIG. 11 is a rear view of the base portion of the tool container;

FIG. 12 is a right side view of the base portion of the tool container; and,

FIG. 13 is a top view of the base portion of the tool container.
